DESIGN FOR A DISH OR SIMILAR ARTICLE

George A. Baker, Walnut Park, Calif., assignor to Max Weil

Application December 24, 1946, Serial No. 135,740

Term of patent 14 years

(Cl. D44—15)

To all whom it may concern:

Be it known that I, George A. Baker, a citizen of the United States, residing at Walnut Park, California, in the county of Los Angeles and the State of California, have invented a new, original, and ornamental Design for a Dish or Similar Article, of which the following is a specification, reference being had to the accompanying drawing, forming part thereof.

The figure is a plan view of a dish, showing my new design.

The dominant features of my design reside in the portions shown in full lines.

I claim:

The ornamental design for a dish or similar article, as shown and described.

GEORGE A. BAKER.
